UNITED STATES PATENT OFFICE

ERNEST BALDWIN MILLER, OF BALTIMORE, MARYLAND, ASSIGNOR TO SILICA GEL CORPORATION, OF BALTIMORE, MARYLAND, A CORPORATION OF MARYLAND

REFRIGERATION METHOD AND APPARATUS

Application filed February 26, 1926. Serial No. 90,827.

The present invention relates to a method and apparatus for refrigeration, and more particularly to the type of refrigeration wherein a liquid is evaporated and the vapor adsorbed in a solid, porous adsorbent.

The main object of the invention is to provide an improved, fully automatic apparatus of this type wherein there is no compressor, pump or similar machinery.

Another object of the invention is to provide an apparatus that requires no attendance, and is thoroughly dependable and fool-proof so that it is suitable for the most exacting requirements, for example, refrigerating railroad cars.

The principal features of novelty are as follows:

1. An automatic control of the valve in the conduit connecting the evaporator and adsorber, so that the valve is open when the porous material is adsorbing vapor, and is closed when the material is being activated and cooled.

2. Automatic means to keep the ice-making evaporator at a lower temperature than the evaporator used for cooling the refrigerating chamber.

3. The means and method of ridding the system of permanent gases without employing a pump, so that no permanent gases are present in the adsorber to interfere with the rapid adsorption of vapor from the evaporator.

4. A condenser which permits activating the adsorbing material rapidly. This is obtained by condensing part of the vapor, liberated during activation, at sub-atmospheric pressure and the balance at a higher pressure.

5. Ridding the system of permanent gases by venting them from the second stage of the condenser, to the atmosphere.

6. Venting the permanent gases from the condensed vapors when the latter are hot. Because the condensed vapor is hot, there is a minimum of air entrained therewith.

7. Controlling the return of the condensed vapor to the evaporator so that it varies inversely with the refrigerating effect being obtained; that is, the higher the temperature of the liquid in the evaporator of the refrig-

erating chamber, the more rapid the return of the condensed vapors to the evaporator.

8. Automatically controlling the activation of the adsorbing material. This activation may be governed by the refrigerating effect as indicated by the temperature of the liquid in the evaporator; also by the amount of vapor condensed in the condenser and by the temperature of the vapor liberated from the adsorbing material. The activation, after it is initiated, continues until the temperature of the liberated vapor falls, or in other words, until practically all of the vapor is liberated from the adsorbing material.

9. Means connecting the two stages of the condenser so that vapor and condensate from the first stage are not discharged into the second stage until the pressure in the first stage slightly exceeds that in the second.

10. Means connecting the adsorber and the condenser, which cuts off communication between these two parts when the adsorber is adsorbing vapor but permits discharge of vapor to the condenser when the adsorbing material is being activated.

11. In an apparatus having a plurality of adsorbers, means for activating said adsorbers in rotation, the intervals between successive activations depending upon the refrigerating effect; that is to say, the warmer the liquid in the evaporator, the more frequent the activations.

Other features of novelty will be apparent from the description taken in connection with the drawings, in which:

Figure 17 is a diagrammatic elevation of a modification.

Referring to Fig. 1 of the drawings, the form of apparatus there shown comprises an evaporator E adapted to contain an evaporable liquid such as brine, an adsorber A in communication therewith and charged with a solid, porous adsorbing material such as silica gel, and a condenser C adapted to condense the vapor liberated from the adsorbing material and return it to the evaporator.

The evaporator may be of any suitable construction to present as large a surface as possible. In the form shown, it comprises a series of horizontal superposed manifolds 20, 21, 22 and 23. As shown in Fig. 15, each of these manifolds comprises a header 24 and a series of tubes or pipes, each of which is closed at one end and at the other end welded to the header. Each header has at one end an upwardly inclined portion 26 connected to a riser 27. The vapor evaporated from the liquid in the manifolds flows through the inclined portions 26 to the riser 27. As explained hereinafter, liquid is supplied to the upper manifold and overflows through a tube 28 into the second manifold. Likewise, each of the manifolds is provided with an overflow tube 28 for supplying the next lower manifold. The upper ends of the tubes 28 project into the headers 24 so that liquid cannot overflow until it has accumulated to such an extent as to reach the level determined by the upper ends of the tubes 28.

It will be noted that this evaporator pre-

sents a large external surface so that it is responsive to changes of temperature in the refrigerating chamber. It also holds the liquid in such manner that a large surface is provided for evaporation. This also aids in making the evaporator quickly responsive to changes in temperature in the refrigerating chamber.

If it is desired to provide means for making ice, then an additional evaporator 29 may be provided. As shown, this may be in the form of a tank having depressions 30 in its upper side to receive cans or forms containing the water to be frozen. Vapor from the liquid in the tank 29 passes out through the pipes 31 and 32 leading to a riser 33. The tank 29 may be supplied with liquid from the lower manifold through an overflow pipe 34 similar to the overflow pipes 28.

The vapor from the evaporator is conducted to the adsorber. For this purpose the risers 27 and 33 communicate with a conduit 35 leading to the adsorber. In order to make ice in the ice-making evaporator, the temperature of the brine therein should be 10° to 18° F., which is lower than the temperature of the brine in the upper evaporator. To obtain this result, at the beginning of an adsorption cycle communication between the upper evaporator and the adsorber is cut off until the temperature of the brine in the lower evaporator has been reduced to some predetermined temperature (say 10° to 18° F.). Then the riser 27 is placed in communication with the adsorber and remains so until the end of the adsorption cycle. This may be accomplished by a valve 36 controlled by a thermostat having a temperature responsive element 37. As shown, this element is disposed in the ice-making tank.

One form of the valve 36 is shown in detail in Fig. 12. It comprises a body 38 having an inlet 39 to which the riser 27 is connected, and an outlet 40 to which the conduit 35 is connected. Within the body is a valve seat 41 with which the valve member 42 co-operates. The valve 42 is moved to and from the seat 41 to control the flow of vapor from the evaporator. For this purpose the valve 42 is carried by the end member or diaphragm of a bellows-tube 43 of metal or other suitable material which, at the end opposite the valve, is secured to the valve body. As shown, this is accomplished by securing the end of the bellows to a flange 44 on a tube 45 which projects through the removable end wall 46 of the valve body. This tube has a small bore and the end of the tube 47 extending to the temperature responsive element 37 is secured therein as by sweating or welding. The joint between the flange 44 and end wall 46 must be absolutely gas-tight and so the tube 45 is welded at 48 to the end wall. To relieve strain on this

welded connection, the end of the tube 45 is threaded and has a nut 49 screwed thereon which bears against a sleeve 50 which in turn is forced against the end wall 46. Thus, 5 by screwing up the nut 49, the end wall 46 is clamped between the flange 44 and the sleeve 50.

The thermostat, comprising element 37, tube 47, and bellows-tube 43, is filled with a 10 suitable liquid that will expand the bellows when the temperature rises. Thus, when the temperature of the brine in the ice-making evaporator 29 is above the predetermined value, the valve 43 is held against its seat 15 and no vapor is evaporated from the upper evaporator. The ice-making evaporator, on the other hand, is in direct communication with the conduit 35 by means of the riser 33, so that vapor is evaporated from the same, 20 whereby the temperature of the brine therein is rapidly reduced. When this temperature has been lowered to the predetermined value, the valve 42 opens, thereby placing the upper evaporator in communication with the conduit 35. This valve remains open during the 25 balance of the adsorption cycle.

The conduit 35 leads to a valve housing 51, which in turn communicates with the header 52 of the adsorber. In the form of 30 adsorber here shown, the header 52 has a plurality of pipes 53 welded thereto, the lower ends of the pipes being closed. A tubular screen 54 (Fig. 14) is fastened in each pipe, extending throughout the length thereof, and projecting into the header. The annular spaces between the screens and inner surfaces of the pipes are filled with silica gel or other suitable adsorbent. Of course, as 35 many of these adsorber units or manifolds will be used as are necessary to give the required refrigeration. For the smaller units, one section is sufficient. This adsorber manifold is surrounded by a heat insulating casing 55, the upper end 56 being funnel-shaped 40 and provided with a damper 57 which controls communication with the atmosphere. Any suitable means may be used for activating the adsorbing material. In the form 45 of apparatus illustrated, a gas burner 58 is disposed at the lower end of the casing 55 and below the tubular adsorber unit, a suitable opening 59 being provided for the admission of air.

An advantage of this vertical arrangement 50 of adsorber tubes within the casing is that a chimney effect is thereby obtained which insures proper distribution of the heating medium around and along the entire length of the tubes, when the adsorbing material is being activated, and also induces a current of air upwards within the casing so as to cool the adsorbing material after activation and during the adsorption cycle.

A valve 60 within the casing 51 controls 55 communication between the adsorber and the

evaporator. Normally this valve is open, but when the adsorbing material is being activated, this valve is automatically closed. For this purpose the lower end of the stem 61 of the valve rests on a bellows-tube 62 of the 50 type already described. The interior of this bellows is in communication, through tube 63, with a temperature responsive element 64, disposed adjacent the tubes of the adsorber. Normally the temperature of the adsorber is relatively low and the bellows 62 is therefore contracted, the spring 65 holding the valve open. As soon as the heating means is turned on to activate the adsorbing material, the element 64 is affected, expanding the bellows 62 and closing the valve 60, thereby cutting off communication between the evaporator and the adsorber. This valve will remain closed until the temperature in the adsorber drops sufficiently to permit contraction of the bellows 62, when it opens being aided by spring 65.

During activation of the adsorbing material, the vapor liberated is discharged into the valve casing 61 which, below the valve 60, has communication with a condenser. As shown, the vapor flows from the valve casing 51 through a short tube 66 into a chamber 67 in a housing 68. This housing is divided into two chambers by a horizontal partition 69. The lower chamber is partially filled with a liquid, like mercury, and a tube 70 projects from the partition 69 downwardly so that its lower end is submerged in the mercury. Above the surface of the 100 mercury and below the partition 69, this chamber has communication, by means of a tube 71, with another small housing 72. When the vapor liberated from the adsorber has its pressure slightly increased, it flows 105 from the chamber 67 downwardly through the tube 70 and bubbles up through the mercury, then flows through tube 71 into the housing 72. The housing 68 with the partition 69, tube 70 and the mercury thus constitutes a seal or check valve to prevent vapor passing directly to the condenser when the adsorber is adsorbing. The chamber 67 is of sufficient size to hold all the mercury, so that if anything should occur to force the 110 mercury through tube 70 into said chamber, it would not pass over into any other parts of the apparatus. The housing 72 contains a temperature responsive element 115 73 for a purpose presently to be described.

The condenser connected with the housing 72 is preferably in two parts so that part of the vapor is condensed under sub-atmospheric pressure and the balance at atmospheric pressure. It will be understood that the evaporator, adsorber and parts already described, are under vacuum and contain no permanent gases. If any permanent gases leak into the system, the rapidity with which the adsorbing material will adsorb the va-

pors is retarded. Even the slightest amount of permanent gases will materially affect the rate of adsorption.

The first stage of the condenser is shown at 74 and has one end connected to the housing 72 and the other end to a small condensate tank 75. This stage of the condenser is under vacuum.

The second stage of the condenser is shown at 76. The vapor condensed collects in a tank or receptacle 77 having a vent 78 open to the atmosphere. The stage 76 of the condenser is therefore at atmospheric pressure.

The two stages of the condenser are connected so that when the pressure of the vapor being condensed in the first stage builds up to such an extent as to slightly exceed atmospheric pressure, it discharges into the second stage. For this purpose a check valve may be used to connect the two stages. As shown, a mercury check valve is employed. It comprises a closed casing or tank 79 containing mercury 79^a. This tank is connected to the tank 75 through a vertical length of pipe or tube 80. The tube is of such length that the difference of levels between the mercury in the tank 79 and that in the tank 75 is about 30 inches. The second stage condenser 76 communicates with the tank 79 through the tube 81. The lower end of the tube 80 is submerged in the mercury 79^a. The tank 79 is a little larger than necessary to contain all of the mercury, so that only a slight increase above atmospheric pressure is required to force fluid from the first stage to the second. The pressure in the second stage of the condenser being substantially atmospheric, a column of mercury of about 32 inches in height is maintained in the tube or pipe 80. When, during activation, the pressure in the first stage of the condenser builds up, this mercury is forced down the pipe 80 into the receptacle or tank 79 and finally when the pressure in the first stage exceeds that in the second, vapor and condensate will be discharged from the lower end of the tube 80 and bubble up through the mercury 79^a and then flow through the pipe 81 into the second stage 76 of the condenser. The first stage of the condenser is designed to have a capacity to condense only a part of the vapor liberated, so that gradually the pressure of the vapor in this first stage will increase until it becomes sufficient to cause discharge into the second stage.

If all the liberated vapor were condensed at atmospheric pressure, it would be necessary to heat the entire mass of adsorbent to the temperature corresponding to this pressure before any vapor would be discharged into the condenser. With the two stage method, vapor begins to be liberated and condensed, almost immediately following the ignition of the burner. By the time the pressure in the first stage has increased to atmospheric, a con-

siderable portion of the vapor has been liberated from the adsorbent. In other words, the two stage method permits liberating and condensing a considerable portion of the adsorbed vapor before any vapor would be liberated and condensed by the single condenser at atmospheric pressure. Consequently the two stage method greatly reduces the period of time required for activation. 70

The tank 77 in which the condensate collects has a pipe 82 leading to the upper manifold of the evaporator so that the condensate is returned to the evaporator through this tube 82. A cooling device 82^a may be provided, if desired. The flow of the condensed vapor back into the evaporator is controlled by a valve 83. One form of valve suitable for this purpose is shown in Fig. 11. It comprises a body 84 having an inlet to which the pipe 82 is connected and an outlet 85 leading to the evaporator. The flow from the inlet to the outlet is controlled by a valve 86 cooperating with a valve seat 87. This valve 86 is carried on the end wall of a bellows-tube 88 of the same construction as described in connection with valve 36, and secured to the valve body in the same way. A temperature responsive element 89 in the evaporator is connected by a tube 90 with the bellows 88. When the temperature of the brine in the evaporator rises, the bellows 88 is expanded, thereby opening valve 86 and permitting return of condensed vapor to the evaporator. The evaporator being under vacuum and the tank 77 at atmospheric pressure, there is no difficulty in effecting this return. 95

The starting and stopping of the activation of the adsorbing material is effected automatically. As shown, a gas or fuel supply pipe 91 is connected to a valve 92, the outlet of which is connected by means of pipe 93 to the burner 58 under the adsorber unit. This valve is normally closed, but means is provided so that it is opened when the amount of condensate in the tank 77 is sufficiently reduced. As the discharge of condensate from the tank 77 to the evaporator is controlled by valve 83 in turn responsive to the temperature of the brine, it will be seen that the fuel valve 92 is thus indirectly controlled by the temperature of the brine. 100

One form of valve 92 and the device for controlling the same is shown in detail in Figs. 6, 7 and 8. The valve proper comprises a valve body 94 divided into two compartments 95 and 96 by means of a partition 97. The inlet pipe 91 communicates with the compartment 96 and the outlet pipe 93 with the compartment 95. The partition 97 has an opening 98 thereto, and this opening, in the form shown, is controlled by a ball valve 99. Normally this valve is seated in the opening, thereby closing the same. Means is provided to move it from its seat and thus supply fuel to the burner under the adsorber when 110

the amount of condensate in the tank 77 falls sufficiently. For this purpose, there is a float 100 in the tank which carries a stem 101 that projects vertically upward and outside of the tank 77, and at its lower end is provided with a fluted guide 102 slidable in the outlet passage 103. This passage is closed by the conical valve 104 when the float falls sufficiently to permit the valve seating. The tank 77 at its upper end is provided with a tubular extension 105 to which is welded a horizontal flange 106, and this flange supports the valve 92. The stem 101 at this point is guided for vertical movement by a sleeve 107 carried by a flange 108 clamped between the flange 106 and a flange 109 on the lower end of an upwardly extending tubular housing 110. The vent 78, previously mentioned, is provided in this flange 108. A portion of the housing 110 is cut away as shown at 111 for the means connecting the valve and the float stem, which means actuates the valve. As shown, the stem 101 has a collar 112 set-screwed thereto, and this collar carries an adjustable screw 113 the projecting end of which is adapted to contact with a lever 114 rigidly secured to a short shaft 115 extending into the compartment 96 of the valve body. Within the valve body the shaft 115 has secured thereto a depending arm 116 which in turn near its free end engages the lever 117 near its pivot. The lever 117 in turn near its free end engages a bent lever 118 pivoted at 119. The free end of this bent lever 118 engages the ball valve 99. Thus when the lever 114 is depressed, the amount of movement transmitted to valve 99 is greatly magnified. In other words, a very slight movement of lever 114 will push valve 99 from its seat. The lever 114 is made in two parts pivoted together at 120 and held against breaking by spring 121. This construction is provided so that if the motion of the float is so great as to force lever 118 against the partition 97, the lever 114 can yield. The valve actuating parts are held in the position shown in Fig. 6 by the spiral spring 122 on the shaft 115.

This structure provides a means for opening the valve suddenly instead of gradually. Means is also provided to hold the valve in this open position until substantially all of the vapor has been liberated from the adsorbing material. It will be seen that liquid will gradually accumulate in the tank 77, while the adsorbing material is being activated, and this would cause the float to rise and close the valve before all of the vapor had been liberated from the adsorbing material. To prevent this, the housing 110 above the upper end of the float stem 101 supports a bellows-tube 123 of the type already described. This bellows is in communication with the temperature responsive element 73 through the tube 124, these parts, like the other thermostats already described, being

filled with a suitable liquid so that changes in temperature in the temperature responsive element will cause expansions and contractions of the bellows 123. The lower end of the bellows carries a member 125 provided with a socket into which the upper end of float stem 101 projects. After the fuel valve has been turned on, and activation of the material started, the vapor liberated will come in contact with temperature responsive element 73. This vapor being hot will expand the liquid in the element, thereby expanding bellows 123 and forcing member 125 down against the upper end of the float stem 101. Thus the float stem will be held in position to keep the fuel valve open until such time as the temperature of the vapor around the temperature responsive element 73 falls. This will not occur until substantially all of the vapor has been liberated from the adsorbing material. During this period of activation, of course liquid has been accumulating in the tank 77 tending to raise float 100 and thereby close valve 99. So, when the temperature responsive element 71 permits contraction of the bellows 123, the float will rise, permitting valve 99 to seat and cut off further supply of fuel.

During this activation, the vapor liberated fills the adsorber, condenser and associated parts, thereby driving ahead of it any air or permanent gases, in the same manner that air is driven out of a steam-heating-radiator when the steam is turned on. Any air or permanent gases that have leaked into the system or accumulated in any way are thus vented through the opening 78 from the tank 77. As the liquid in this tank is at an elevated temperature, practically no air will be entrained therewith when it is discharged from the tank and returned to the evaporator.

After the apparatus has been built, to produce the vacuum therein and render the plant ready for operation, any suitable method may be employed. If desired, a vacuum pump may be connected to any suitable part of the apparatus to exhaust the air. Preferably, however, the adsorber is heated, thereby driving off vapor from the adsorbing material and expelling air through the vent opening 78. Perhaps all of the air or permanent gases will not be eliminated from the system the first time, but enough will be discharged so that the refrigerating cycle will continue automatically. After one or two activations, all of the permanent gases will have been eliminated from the system, and thereafter the small amounts that may leak in or accumulate will be expelled during each activation.

The operation of the apparatus may be briefly summarized as follows:

Vapor is evaporated from the evaporator and conducted by a pipe 35 to the adsorber. Where the evaporator is provided with an

ice-making part, the first part of this vapor comes from said ice-making compartment, the valve 36 cutting off the flow of vapor from the upper portion of the evaporator.

5 After the brine in the ice-making compartment has its temperature sufficiently lowered, the valve 36 opens so that thereafter during the adsorption cycle, vapor is also taken from the upper evaporator.

10 During this time, condensed liquid in the tank 77 is being returned to the evaporator through the pipe 82, the valve 83 controlling the flow in accordance with the refrigerating effect, that is to say, the lower the tempera-

15 ture of the brine, the smaller the return flow of this liquid. Finally, when enough liquid has been discharged from tank 77, the float 96 falls sufficiently so that gas valve 92 is opened. Gas is thus supplied to the gas burn-

20 er 58 under the adsorber unit and is ignited by the pilot light 126. Now the adsorber is heated and vapor is liberated from the adsorbing material and discharged into the condenser. The first portion of the vapor liber-

25 ated from the adsorbing material is condensed under vacuum in the first stage 74 of the condenser. Finally, the pressure in this first stage of the condenser builds up sufficiently so that it discharges into the second stage or

30 atmospheric condensing stage of the condenser. Then the balance of the vapor is condensed at atmospheric pressure. All of the condensate collects in the tank 77. The hot vapor coming over from the adsorber strikes

35 the thermostat element 73, thereby expanding bellows 123 into contact with the stem 101 of the float 100, thus holding the gas valve 99 open until substantially all of the vapor is driven off from the adsorbing material.

40 Then the temperature of this vapor falls so that the bellows 123 contracts and valve 99 may close if sufficient liquid has accumulated in the tank 77. After the supply of heating medium has been turned off in this manner,

45 cool air enters at the bottom of the adsorber casing and flows upwardly around the tubes, thereby cooling the same. After a time the pressure in the adsorber falls sufficiently so that the valve 60 opens and another absorbing

50 cycle is started.

As stated, preferably a brine is used as the refrigerant, but other liquids that can be evaporated under the conditions might be used. It is also preferred to use highly porous 55 granular silica gel in the adsorber, but other adsorbent gels or materials might be used if they have sufficient adsorbent capacity. As a measure of the adsorptive capacity of an adsorbent suitable for this invention, it may be said that it should have enough small pores so that it will adsorb at least 10% of its own weight of water when in equilibrium with water vapor at a temperature of 30° C. and a partial pressure of 22 mm. of mercury.

60 Although the invention has been described

as employing gas for the heating medium, it is obvious that electricity, kerosene or other suitable heating mediums might be employed. Of course, if electricity were used, the valve 92 would be replaced by an electrical valve, that is to say, a switch.

Another method of controlling the fuel valve 92 is illustrated in Fig. 13. In this modification, the valve is controlled directly by the temperature of the brine in the evaporator, instead of indirectly from this source through the float. The vapor condensed in the condenser collects in the tank 77 and is returned to the evaporator through the pipe 82 in the same manner as already described.

80 For controlling the gas valve, there is provided a temperature responsive element 140 in the brine in the evaporator. This element is connected by means of a tube 141 with a bellows-tube 142. These elements are filled with a suitable liquid and constitute a thermostat.

85 The lower end of the bellows-tube 142 is disposed to contact with the valve lever 114 of the same construction as described in connection with the first form of the invention.

90 When the temperature of the brine rises, the bellows 142 expands, thereby depressing the lever 114 and opening the gas valve. The lever is held depressed, and thus the valve open until substantially all

95 of the vapor has been liberated from the adsorbing material, by means of a second thermostat, consisting of the temperature responsive element 73, already described, and a tube 143 connecting this element to a bellows-

100 tube 144, adapted to contact with the lever 114. The hot vapor being liberated from the adsorbing material expands the liquid in the thermostat, by coming in contact with the temperature responsive element 73. The ex-

105 pansion of this liquid causes the bellows 144 to expand and hold the lever 114 depressed until such time as substantially all of the vapors have been liberated from the adsorbing

110 material.

In Fig. 16 is illustrated a form of the apparatus in which the valve 36, previously described, is eliminated. In this construction, the upper evaporator E is charged with a

115 weaker brine than the ice-making evaporator 29. The brine in the latter is of such concentration that it will freeze at about 10° to 15° F. When the apparatus starts on an adsorbing cycle, vapor is evaporated from both

120 the upper evaporator and the ice-making tank. The temperature of the brines in these two evaporators falls, and soon the weaker brine, that is, the brine in the upper evaporator, freezes. As a result, no further evap-

125 oration takes place from this evaporator until the ice is melted. On the other hand, evaporation from the lower or ice-making tank, continues so that the brine in this latter evaporator has its temperature lowered to the point where it will freeze the water in the

containers 30. Finally, the brine in this ice-making tank also freezes so that evaporation from this tank is thus ended. By this time, or shortly, the ice in the upper evaporator will have melted so that evaporation continues from the upper evaporator. It will be seen, therefore, by using brines of two concentrations, it is possible to secure the result of lowering the temperature of the brine in 10 the ice-making tank sufficiently to freeze the water in the containers, and this can be effected without the valve 36.

For the larger installations, it is desirable to have a plurality of adsorber units or manifolds. By providing several of these units, each of a relatively small capacity, and activating the same frequently, the adsorbing material is utilized to a maximum degree. Furthermore, the total weight of adsorbent 20 for a plant of given capacity may be a minimum.

An apparatus of this type is diagrammatically illustrated in Figs. 2, 3, 4, 5, 9 and 10. Referring to Fig. 2, the evaporator may 25 be of the same construction as already described, and may or may not have the ice-making compartment, as desired. It is connected with the adsorber assembly by means of a conduit 150, which ends in a header 151. 30 In the form illustrated, there are three adsorber units, A¹, A² and A³, each consisting of an adsorber manifold like that already described, and each disposed within a heat insulated casing. Each casing has a burner 35 152, 153 and 154 near the bottom thereof and a damper at the top to control the circulation of the heating medium and the cool air.

The vapor from the evaporator is thus conducted to the header 151 and passes through 40 the vapor valves 155, 156 and 157 to the adsorber sections A¹, A² and A³, respectively. These individual valves 155, 156 and 157 provide means so that the adsorber sections can be cut off from the evaporator when being activated. A vertical section through these 45 valves is shown in Fig. 4. The parts are shown with valves 156 and 157 open and valve 155 closed, as the adsorber section A¹ is being activated. Each of these valves may 50 comprise an upper bellows-tube 158, a lower bellows-tube 159 and a spindle 160, connecting the two which carry the valve member 161 adapted to seat against the partition 162 and close the opening therethrough. The 55 lower bellows-tube 159, as illustrated in Fig. 3, is connected by means of a tube 163^a to a temperature responsive element 163, disposed adjacent the tubes of the adsorber. It will be understood that there is one of these temperature responsive elements for each of the bellows-tubes 159 so that the bellows 159 will 60 be responsive to the temperature of its particular adsorber section. The diaphragm 164 of the upper bellows-tube 158 carries a vertical spindle 165 aligned with the valve spin-

dle 160. This spindle 165 projects above the top of the valve proper, for a purpose presently to be described.

When the vapor valve is closed and the adsorber section is being activated, vapor liberated from the adsorbing material will pass into the valve casing, then through conduit 166 (Fig. 3) into a chamber 67 of a casing 68 of the same construction as described in connection with the first form of the apparatus. It will be understood that there is one of these casings 68 for each of the vapor valves. The vapor then passes from chamber 67 downwardly through the tube 70, bubbles up through the mercury in which the lower end of this tube is submerged, and then passes through a short tube 167 into a header 169. This header discharges into the condenser which may be of the same construction as already described. Near the discharge end of this header 169 is a temperature responsive element 170, connected by a tube 171 to a bellows-tube 123, the same as described in connection with the first form of the apparatus, this bellows-tube acting to hold the fuel valve 65 open as long as any vapor is being discharged from the adsorber section being activated.

Means is provided so that each of the adsorber sections will be activated in rotation, and at intervals depending upon the temperature of the brine in the evaporator or the amount of vapor condensed. For accomplishing these ends, the gas valve 92 is connected by means of a pipe 172 to a distributor D. This distributor, as shown in Fig. 9, 100 has a chamber 173 into which the pipe 172 discharges, and which, through individual valves 174, may be placed in communication with pipes 175, 176 and 177 leading respectively to the burners 154, 153 and 152. The 105 valves 174 are opened in rotation and successively by means of a cam 178 on a plate 179 non-rotatively mounted on a shaft 180. There is provided for each of the stems of the valve 174, a rocker 181 which engages the end 110 of the stem and carries a roller 182 adapted to be acted on by the cam 178. Thus, as the shaft 180 is rotated, cam 178 will successively engage rollers 182 and thus open the valves 174 in rotation.

The movements of the vapor valves 155, 156 and 157 are utilized to rotate the disc 179 at the proper times. For this purpose, the shaft 180 at one end has a gear 183 (Fig. 5) which meshes with a gear 184 mounted to rotate with a ratchet wheel 185. A shaft 186 is disposed above the top of the vapor valves 155, 156 and 157 and has secured thereto arms 187, 188 and 189, one arm for each valve. At the end of the shaft adjacent the ratchet wheel 185, it carries a pawl arm 190 on which is mounted a pawl 191, co-operating with the ratchet wheel 185. A spring 192 (Fig. 5) tends to rotate the pawl arm 190 in a clockwise direction, as viewed in Fig. 10.

The upper end of each of the valve stems 165 is adapted to engage one of the arms 187, 188 and 189. In the position of the parts shown in Fig. 4, the left-hand valve stem 165 has engaged the arm 187, thereby rotating the shaft 186 and turning the pawl arm 190 in a counter-clockwise direction, as viewed in Fig. 10. This valve stem is associated with the valve 155 and adsorber section A¹, 10 which is being activated at this time. After the activation has been completed, the valve member 161 of the valve 155 will open, thereby lowering valve stem 165 and permitting shaft 186 to turn in a clockwise direction, as 15 viewed in Fig. 10. The spring 192 will effect this rotation and it will be communicated, by means of pawl 191 to the ratchet wheel 185, which, through the gearing, will rotate the disc 179 and bring cam 178 under the next 20 roller, thereby opening the next valve 174, so that the next time the main gas valve 92 is opened, the adsorber section A² will be activated. This will occur when the float falls sufficiently to open the main gas valve 92. 25 Then the burner 153 of the adsorber A² will be ignited and temperature responsive element 163 will thereby be heated, causing the valve 156 to close. This closing movement will raise stem 165 thereby through arm 188, 30 rotating arm 186 in a counter-clockwise direction, as viewed in Fig. 10, so that when this valve 156 later closes, rotation of the shaft in the return direction will permit rotation of the cam disc 179, thereby opening the next 35 gas distributor valve 174 and placing the parts in position so that the next time the main gas valve 92 opens, the adsorber section A³ will be activated. It will be seen, therefore, that the adsorber sections are activated in succession and at intervals, depending upon the temperature of the brine in the evaporator.

Fig. 17 shows a modified arrangement of the parts between the condenser and the 45 evaporator, it being understood that the parts shown in this figure are adapted for use with the single unit adsorber shown in Fig. 1 or with the plurality of adsorber units shown in Fig. 2.

50 The arrangement shown in Fig. 17 is designed to accomplish two purposes as follows:

1. To regulate the adsorption period for the upper evaporator and the lower, or ice-making, evaporator.

55 2. To prevent air entering the evaporator from the float chamber in case the water leaks out of the latter.

The evaporator E may be of any suitable 60 construction and is designed for refrigerating the chamber and the evaporator E' for making ice as previously described. Consequently the brine in the evaporator E' must be kept at a lower temperature than that in 65 the evaporator E.

The vapor evaporated from the evaporator E passes through pipe 200 to the casing 201. Projecting from the bottom wall of this casing is an annular partition 202. A conduit 203 leading to the adsorber projects through the said bottom wall and into the space enclosed by the annular partition 202. The ice-making evaporator E' is in communication with the conduit 203 by means of a pipe 204. A cap 205 is disposed over the upper end of the conduit 203. The vertical wall of this cap is luted in mercury 206 in the annular space between the conduit 203 and the partition 202. As described hereinafter, the level of the mercury 206 rises and falls in 70 accordance with the amount of water above the float in the associated part of the apparatus. The cap 205 is kept out of contact with the upper end of the conduit 203 by being carried on the float 207 disposed in the mercury 75 208 in the annular space between the partition 202 and the outer wall of the casing 201. This mercury 208 is the upper portion of the barometric column 209, so that the level X of mercury rises and falls with changes in 80 the atmospheric pressure. The annular space just inside of partition 202 is in communication with a chamber 210 by means of the tube 211. This chamber in turn is connected by 85 means of tube 212 to a float chamber 213. The vapors condensed in the condenser C flow into the casing 214 which at 215 has a vent to the atmosphere and which is connected by tube 216 with the float chamber 213. The mercury in the space within the 90 partition 202, the tube 211 and chamber 210 is balanced by the water column in tube 212, float chamber 213 and tube 216 and the atmospheric pressure on the top of the water in the casing 214. Consequently the level of 95 the mercury 206 varies with atmospheric pressure and the height of the column of water just mentioned. Inasmuch as the level X of mercury depends on the atmospheric pressure, and the level of mercury 206 depends upon atmospheric pressure and the water column, the difference of levels will be due solely to the water column. Any 100 changes in atmospheric pressure will not change the relative difference of these two mercury levels. So when the height of the water column decreases, the mercury level 105 206 will fall until it is below the lower edge of the cap 205. This will place the evaporator E in communication with the conduit 203, and this communication will not be interrupted until the height of the water column is increased the necessary amount.

110 From the foregoing it is apparent that the ice-making evaporator E' is always in communication with the conduit 203, whereas evaporator E is not in communication with said conduit until the height of the water column decreases. So when beginning an 115 adsorbing cycle, vapor is first taken from the 120 125 130

ice-making evaporator E', thereby rapidly lowering its temperature to the desired point. During this time the water level in casing 214 and conduit 216 has fallen so that at the 5 desired point communication is established between evaporator E and conduit 203, because of the mercury level 206 falling below the cap 205. Thereafter vapor will be taken from the evaporator E as well as from the 10 ice-making evaporator E'.

The water condensed in the condenser C flows into the casing 214, conduit 216, casing 213, tube 212 and chamber 210. The float 217 controls the gas valve 92 in the manner 15 described in connection with the other forms of the invention. The atmospheric pressure on the condensed water forces it from chamber 210 up tube 218 to the valve 83 described in the other forms of the invention, which 20 controls the rate of the return of the water to the evaporator E.

In the operation of these parts, at the close of a period of activation, the water level in casing 214 is relatively high because the vapor 25 driven off from the adsorbing material during activation has been condensed and collected. Consequently, the cap 205 is luted in the mercury 206, and when the adsorbing period begins, communication between evaporator 30 E and the adsorber is thereby cut off, but there is communication between the adsorber and the ice-making evaporator E'. The brine in E', therefore, is rapidly cooled to the desired temperature. The water level in casing 35 214 and tube 216 gradually falls because the water is being continually returned to the evaporator E. When the water level has fallen to a desired point, say 219, the mercury level 206 has fallen a sufficient amount so as 40 to be just below the bottom edge of the cap 205. Evaporator E is thereby placed in communication with the adsorber conduit 203 and the brine in evaporator E is then chilled to the desired temperature. The water level 45 219 continues to fall and finally reaches the level, say 220, when the float 217 begins to fall, and thereby opens gas valve 92 and starts an activating period. The starting of this activation, as described in connection 50 with the other forms of the invention, causes the main vapor valve adjacent the adsorber to close so that communication between the adsorber and the evaporators is cut off. Very shortly after this activating period has been 55 started, condensed water will flow into casing 214 and the level of water will rise from 220 gradually to the point indicated in casing 214. Then the sequence of steps just described will be repeated.

60 This device, therefore, controls communication between the adsorber and the two evaporators, so that during an adsorption period, vapor is always taken from the ice-making evaporator, but from the refrigerating evaporator, only a portion of the time.

In this manner the brine in the ice-making compartment is kept at a lower temperature than the brine in the refrigerating evaporator.

This device also acts to prevent air entering the evaporator E if the water column falls to such an extent as to open the lower end of tube 218. As previously pointed out, the level of mercury 206 is maintained by the water column and atmospheric pressure on the top of the water column. Consequently, when the water column decreases in height the level of the mercury 206 falls and the mercury 206^a in casing 210 thereby rises. The parts are proportioned so that when the water column falls to the level 221, the mercury 206^a will have risen to a height above the lower end of tube 218, thereby sealing the same. This will prevent the forcing of any more water or air through the tube 218 into evaporator E. Of course, if the water level falls to 221 or thereabouts and the mercury level 219 in the casing 210 rises to a point above the lower end of tube 218, the mercury will enter this tube and rise therein. During 90 the next activating period the water level 221, of course, will rise, thereby depressing the mercury in chamber 210 until the lower end of tube 218 is opened. At the moment this tube is opened, it may be that the first rush 95 of water up through the same would tend to carry some mercury over to the valve 83. To prevent this, the expansion chamber 222 is provided. This takes care of any mercury that might be carried over to said valve, and after the first rush of water, the mercury will 100 fall back into the casing 210.

It will be noted that the valve 104 in the forms of the invention shown in Figs. 1 and 2 has been omitted. This form of the apparatus will act satisfactorily without the valve 104, but if desired the valve may be provided, and in this case the device will act to secure the same objects.

In the normal operation of the apparatus, the water level will not ordinarily fall to any such level as indicated at 221. However, if the refrigerating apparatus is shut down by turning off the supply of gas, the water will gradually be returned to the evaporator so that the level will fall to the point indicated at 221. If the present device were not provided, air would then pass over to the evaporator and the apparatus would become air-bound. With the device described herein, this condition cannot occur, and even if the apparatus has been out of operation for a long period, it can be again set in operation without any difficulties.

Where the float is provided with a valve like 104, this valve will prevent the water from falling to the level 221 unless the valve leaks. So where such valve 104 is provided, the device just described will prevent air pass-

ing over to the evaporator in case such valve leaks.

Where the device shown in Fig. 17 is associated with a plurality of adsorbers such as shown in Fig. 2, the ice-making evaporator is always in communication with one or more adsorbers, so that there is continual evaporation from this evaporator. The evaporator E for refrigerating the chamber, however, is periodically connected with the adsorbers so that evaporation from this evaporator is not continuous.

If desired, the valve 83 and the associated thermostat of all forms of the invention may be replaced by a manually controlled valve.

Preferably silica gel is employed as the porous adsorbing material. In order to give a rule for determining an adsorbent suitable for the present invention, it may be stated that the material should have pores of such size that it will adsorb water vapor to such an extent as to contain not less than 10% of its own weight of water when in equilibrium with water vapor at 30° C. and a partial pressure of substantially 22 mm. of mercury. A good silica gel under these conditions should adsorb from 21% to 40% of its own weight of water. If desired, other gels, such as the gels of tungstic oxide, stannic oxide, aluminum oxide and titanium oxide, might be used provided they are made so as to have the required finely porous structure.

Having thus described the invention, what is claimed as new and desired to be secured by Letters Patent is:

1. A method of refrigeration consisting in evaporating a liquid, adsorbing the vapor in a porous material, in the absence of permanent gases, activating the adsorbent to liberate the adsorbed vapor, condensing the liberated vapor, returning it to the liquid, and maintaining the system free of permanent gases by sweeping the gases out to the atmosphere during, and by, the activation of the adsorbent.

2. A method of refrigeration consisting in evaporating a liquid, adsorbing the vapor in a solid porous adsorbent in the absence of permanent gases, activating said adsorbent to drive off the adsorbed vapor and free the system of any permanent gases, condensing the vapor driven off from the adsorbent, separating the condensate and any permanent gases and returning the condensate to be evaporated again.

3. A method of refrigeration consisting in evaporating a liquid, adsorbing the vapor in a solid porous material in the absence of permanent gases, activating the adsorbent to liberate the adsorbed vapor, condensing the liberated vapor and returning the condensate to the liquid, a portion of said liberated vapor being condensed under vacuum and the remaining portion at atmospheric pressure.

4. The method according to claim 3 with the further step of separating any permanent gases from the condensed vapor.

5. A method of refrigeration consisting in evaporating a liquid, adsorbing the vapor in a solid porous material in the absence of permanent gases, activating said material to liberate the adsorbed vapor, condensing the liberated vapor, collecting the condensate and returning it to the liquid, and controlling the activation jointly by the amount of condensate collected and the temperature of the liberated vapor.

6. A method of refrigeration consisting in evaporating a liquid, adsorbing the vapor in a solid porous material in the absence of permanent gases, activating the material, a portion of the adsorbed vapor being liberated at sub-atmospheric pressure and the balance at atmospheric pressure, and using the material to adsorb more of the vapor evaporated from the liquid.

7. Refrigerating apparatus of the character described including in combination, an evaporator, an adsorber in communication with said evaporator and charged with a solid porous adsorbing material, means to activate said material, two condensers in series between said adsorber and evaporator, one adapted to condense under vacuum and the other at atmospheric pressure and means to return the condensate to the evaporator.

8. Refrigerating apparatus according to claim 7 in which there is a vent to the atmosphere from the atmospheric condenser to permit the escape of permanent gases.

9. Refrigerating apparatus of the character described including in combination, an evaporator, an adsorber in communication with said evaporator and charged with a solid porous adsorbing material, means to activate said material, a condenser between said adsorber and evaporator and means to permit the escape of permanent gases while activating.

10. Apparatus according to claim 9 wherein the means to permit the escape of permanent gases is associated with the condenser.

11. Refrigerating apparatus of the character described including in combination, an evaporator, an adsorber in communication therewith and charged with a solid porous adsorbing material, means to activate said material, means to condense at sub-atmospheric pressure a portion of the vapors liberated from the material during activation and to condense the balance at a higher pressure, and means to return the condensate to the evaporator.

12. Refrigerating apparatus of the character described including in combination, an evaporator, an adsorber charged with a solid porous vapor-adsorbing material, means controlling communication between said evaporator and adsorber, means to activate said

adsorber when said communication is cut off, means to condense the vapor liberated from the material and separate the condensate and permanent gases, and means to return the condensate to said evaporator.

13. Refrigerating apparatus of the character described including in combination, an evaporator, an adsorber charged with a solid porous vapor-adsorbing material, means 10 controlling communication between said evaporator and adsorber, means to activate said adsorber when said communication is cut off, a condenser connected to said adsorber to condense the vapors liberated from the 15 material during activation, means to permit escape of permanent gases from the condensed vapors, and means to cool the condensed vapor and return it to the evaporator.

14. Refrigerating apparatus of the character described including in combination an evaporator, an adsorber in communication therewith charged with a solid porous adsorbing material, means to activate the material, two condensers in series between the 20 adsorber and evaporator one being in communication with the adsorber and adapted to condense a portion of the liberated vapor at sub-atmospheric pressure and the other adapted to condense at a higher pressure, means 25 connecting the two condensers constructed and arranged to permit the discharge from the first condenser to the second condenser when the pressure in the first slightly exceeds that in the second, and means to return the 30 condensate to the evaporator.

15. Apparatus according to claim 14 wherein the means connecting the two condensers is a check valve.

16. Apparatus according to claim 14 wherein the means connecting the two condensers is a mercury check valve.

17. Apparatus of the character described including in combination an evaporator having liquid therein with a large exposed 45 surface, an adsorber in communication therewith and charged with a solid porous adsorbing material, means to activate the material, means to condense the vapors liberated from the material during activation, means to return the condensed vapors to the evaporator, and a valve directly controlled by temperature governing the rate of said 50 return.

18. Apparatus according to claim 17 wherein the valve is controlled by the temperature of the liquid in the evaporator.

19. Apparatus of the character described including in combination, an evaporator, an 60 adsorber in communication therewith and charged with a solid porous adsorbing material, means to activate said material, vapor condensing means having a normally open vent to the atmosphere, a check valve between 65 said condensing means and adsorber and

means to return the condensed vapor to the evaporator.

20. Apparatus of the character described including in combination, two evaporators, an adsorber in communication therewith charged with a solid porous adsorbing material and means controlling the flow of vapor from one evaporator to the adsorber in accordance with the temperature of the liquid 70 in the other evaporator.

21. Apparatus of the character described including in combination an evaporator, an adsorber in communication therewith and charged with a solid porous adsorbing material, a normally open valve between said 80 evaporator and adsorber, means to activate the adsorbing material and heat actuated means to close said valve automatically during said activation.

22. Apparatus of the character described including in combination an evaporator, an adsorber charged with solid porous adsorbing material, a conduit connecting said evaporator and adsorber, a normally open valve in said conduit, means to activate and 90 then cool said material prior to adsorbing, and means to close said valve during said activation and cooling prior to adsorbing.

23. Apparatus of the character described including in combination an evaporator, an adsorber charged with solid porous adsorbing material, a conduit connecting said evaporator and adsorber, a normally open valve in said conduit, means to activate said 95 material, and means actuated by the activating means to close said valve during activation.

24. Apparatus of the character described including in combination, an evaporator, an adsorber charged with a solid porous adsorbing material, a conduit connecting said evaporator and adsorber, a normally open valve in said conduit, means to heat the material to activate it, and means to close said 105 valve when the temperature of the material increases.

25. Apparatus of the character described, including in combination an evaporator, an adsorber charged with a solid porous adsorbing material, a conduit connecting said evaporator and adsorber, a normally open valve in said conduit, means to heat the material to activate it, and means to close said valve when the temperature in the adsorber rises and holds said valve closed until the 110 temperature and pressure fall to amounts suitable for adsorbing.

26. Apparatus of the character described including in combination, an evaporator, an adsorber in communication therewith and charged with a solid porous adsorbing material, means to heat said material to liberate the adsorbed vapors, means to condense said 115 vapors and return them to the evaporator, and means governed jointly by the conden- 130

sate and the temperature of the liberated vapors for controlling said heating means.

27. Apparatus of the character described including in combination, an evaporator, an adsorber in communication therewith and charged with a solid porous adsorbing material, means to heat the material to liberate the adsorbed vapors, means to condense said vapors and return them to the evaporator, means to turn on the heating means and means to hold the same on until the temperature of the liberated vapor falls.

28. Apparatus of the character described including in combination, an evaporator, an adsorber in communication therewith and charged with a solid porous adsorbing material, means to activate said material started and stopped by the temperature of the liquid in the evaporator, and means to condense the vapors liberated during activation and return them to the evaporator.

29. Apparatus of the character described including in combination, an evaporator, a plurality of adsorbers in communication therewith, each charged with a solid porous adsorbing material, means to cut off said communication for each adsorber in rotation and means to activate the material in the adsorber thus cut out, said last mentioned means being actuated by the first mentioned means of the previously activated adsorber.

30. Apparatus according to claim 29 in which the means to activate the adsorbers in rotation is controlled by the temperature of the liquid in the evaporator.

31. Apparatus of the character described including in combination, an evaporator, a plurality of adsorbers in communication therewith and each charged with a solid porous adsorbing material, means to condense the vapors liberated from the adsorbing material and return the same to the evaporator, and means to activate said adsorbers in rotation controlled by the amount of condensate.

32. Apparatus according to claim 31 in which the activating means is also controlled by the temperature of the vapor liberated from the adsorbers.

33. Apparatus according to claim 29 in which the activating means is controlled by the temperature of the vapor liberated from the material.

34. Apparatus of the character described including in combination, an evaporator, a plurality of adsorbers each charged with a solid porous adsorbing material in communication therewith, a valve for each adsorber controlling said communication, means to close said valves in rotation, and means to activate said adsorbers, including a distributor adapted to supply the adsorbers with activating medium in rotation, said distributor being controlled by said valves.

35. Refrigerating apparatus including in

combination, an evaporator, an adsorber in communication therewith and charged with a solid porous adsorbing material, means to activate said material, means to condense the vapors liberated during activation and having a vent to the atmosphere for freeing the system of permanent gases, means to return the condensed vapor to the evaporator, and means to prevent air entering said vent from passing to the evaporator.

36. Refrigerating apparatus including in combination, an evaporator, an adsorber in communication therewith and charged with a solid porous adsorbing material, means to activate said material, means to condense the vapors liberated during activation and having a vent to the atmosphere for freeing the system of permanent gases, means to return the condensed vapor to the evaporator, and means to prevent air entering said vent from passing to the adsorber.

In testimony whereof I hereunto affix my signature.
